Filed Apr. 28, 1965, Ser. No. 84,990

Term of patent 14 years

(Cl. D61—1)

FIG. 1 is a front elevational view of a movie light, showing our new design, the handle being in contracted condition.

FIG. 2 is a side elevational view thereof, the handle being in extended position.

FIG. 3 is a rear elevational view of the light as seen in FIG. 1.

FIG. 4 is a top plan view thereof.

The dominant features of our design reside in the portions shown in full lines.

We claim:

The ornamental design for a movie light, substantially as shown and described.
